Primary Examiner — Jasmine Mlinarcik(74) *Attorney, Agent, or Firm* — Sanchelima & Associates, P.A.; Christian Sanchelima; Jesus Sanchelima(57) **CLAIM**

The ornamental design for dustfree headwear cover, as shown and described.

DESCRIPTION

FIG. 1 is an isometric view of a dustfree headwear cover showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof showing my design.

The broken lines depict claimed stitching.
